UNITED STATES PATENT OFFICE

101,445

DESIGN FOR A LAVATORY

Henry Dreyfuss, New York, N. Y., and Roy H. Zinkil, Oak Park, Ill., assignors to Crane Co., Chicago, Ill., a corporation of Illinois

Application May 15, 1936, Serial No. 62,662

Term of patent 14 years

To all whom it may concern:

Be it known that we, Henry Dreyfuss and Roy H. Zinkil, citizens of the United States, residing at New York and Oak Park, in the counties of New York and Cook, and States of New York and Illinois, whose post-office addresses are 501 Madison Avenue, New York, New York, and 406 North Cuylar Avenue, Oak Park, Illinois, have invented a new, original, and ornamental Design for a Lavatory, of which the following is a specification, reference being had to the accompanying drawing, forming part thereof, in which there is shown a perspective view of the lavatory.

We claim:

The ornamental design for a lavatory, substantially as shown.

HENRY DREYFUSS.
ROY H. ZINKIL.
